UNITED STATES PATENT OFFICE.

ALOIS GLASER, OF DEDHAM, MASSACHUSETTS, ASSIGNOR TO LOUIS E. VOSE, OF WALPOLE, MASSACHUSETTS.

SPOOL.

1,234,150.

Specification of Letters Patent. Patented July 24, 1917.

Application filed August 20, 1914. Serial No. 857,684.

To all whom it may concern:

Be it known that I, Alois Glaser, a citizen of the United States, residing at Dedham, in the county of Norfolk and State of Massachusetts, have invented certain new and useful Improvements in Spools; and I do hereby declare the following to be a full, clear, and exact description of the invention, such as will enable others skilled in the art to which it appertains to make and use the same.

The invention relates to an improvement in the construction of spools or bobbins which are used in wire or textile mills for holding wire, thread, tapes, etc., at different stages of its manufacture, or in the manufacture of materials into which it is incorporated, or more especially as a carrier for the finished product preparatory for shipping.

The object of the invention is to provide a novel and improved spool which is cheap and simple in construction, that may be readily manufactured from tubing and boards of paper pulp, leather, fiber or other similar compositions.

A further object of the invention is to secure a spool which is very strong and adapted to hold heavy material and withstand the rough usage to which such spools are subjected. To this end the invention consists in the features of construction and the combination of parts hereinafter described and referred to in the claims.

The invention will be readily understood from an inspection of the accompanying drawings and the following detailed description of the spool illustrated therein.

In the drawings:

Figure 1 is a front elevation of the spool with parts shown in section;

Fig. 2 is a perspective view of one of the heads of the spool with the plug attached thereto;

Fig. 3 is an end view of the spool;

Fig. 4 is a section of the spool taken on the line 4-4 of Fig. 1 looking in the direction of the arrow.

The spool as shown comprises a tubular barrel or body portion 1 and flat head disks 2-3, secured to the barrel 1 by means of the plugs 5-5 and metallic rods 4 having heads for engaging the outer surface of the heads.

Ordinary wire nails are preferably used.

The heads 2-3 are in the form of flat disks

which may be cut from board of paper, pulp or other suitable material. Bearings 6 may be cut in the heads to receive a supporting shaft and the bearing may or may not be provided with a keyway to lock the spool to the shaft. The bearing 6 is comparatively small in diameter so that the heads are substantially solid disks, thus giving a very strong part in the place where the spool is subjected to the greatest strain. The plug 5 may be formed of a tube of composition similar to that used for the disks above or may be of a different composition and has an external diameter substantially equal to the internal diameter of barrel 1. This plug 70 is securely attached to the solid disk heads 2-3 by means of rods or similar fastening members 4, as shown, three in number, but the number of rods used depends upon the size and the strength of spool desired. The 75 rods are arranged around the outer periphery of the plug and are driven through and have their heads embedded in the disks 2-3 and their ends clenched over the inner end of the plug and extending against its inner periphery. The plug thus attached acts as a reinforcing rib for the practically solid disk head.

In assembling the parts the plugs are attached to the heads by means of the rods 4 and the barrel 1 which is a cylinder formed of paper, fiber, tubing or similar material, is forced over the plugs and rods and the ends brought flush against the heads, thus embedding the rods in the barrel longitudinally and securely locking the barrel to the plugs as clearly shown in Fig. 4. Also the joint between the barrel and the plug is made secure by means of any suitable cement. In some cases it may be necessary to press or cut grooves in the barrel for the reception of the rods in assembling the parts, this depending upon the size of the spool to be made, size of rods and the character of material of which the spool is made.

For many purposes it may be desirable to indurate the parts of the spool by means of a suitable hardening solution. The spool may be treated with the hardening solution before or after the parts are assembled or it may be advantageous to assemble the parts while they are under treatment of such a solution.

It will thus be seen that by this construction a comparatively light spool is obtained

which is very strong and suitable for carrying heavy material. The heads which are subjected to the greatest shocks and jars are substantially solid disks which have not 5 been weakened by removing much material at the center and are further strengthened by the connecting plug and the barrel is securely locked to the heads by means of the rods which are embedded longitudinally in 10 the barrel and anchored to the plugs.

While it is preferred to employ the specific construction and arrangement of parts shown and described it will be understood that this construction and arrangement is 15 not essential except so far as it may be specified in the claims and may be varied and modified without departing from the broader features of the invention.

Having explained the nature and objects 20 of the invention and specifically described one form of spool in which it may be embodied what I claim is:

1. A spool comprising a barrel, head disks at the ends of the barrel having plugs secured to their inner face and fastening means passing between the barrel and plug for securing the plugs to the head disks.

2. A spool comprising a barrel, head disks at the ends of the barrel, plugs secured in

the ends of the barrel, and fastening means 30 passing through the head disks and between the barrel and plugs in such a manner as to be embedded in the walls of the barrel to lock the barrel and plugs to the head disks.

3. A spool comprising a barrel, head disks 35 at the ends of the barrel, plugs in the ends of the barrel, fastening means passing through the head disks and between the plugs and the barrel to secure the plugs to the head disks.

4. A spool comprising a tubular barrel, heads at the ends of the barrel, plugs in the ends of the barrel, fastening rods passing through the heads and between the plug and the barrel and clenched over the inner ends 45 of the plugs.

5. A spool comprising a tubular barrel, head disks at the ends of the barrel, plugs secured in the ends of the barrel and rods for securing the head disks in position passing through the head disks and wedged between the barrel and plugs to lock the head disks to the barrel and plugs.

ALOIS GLASER.
